SPECTACLE FRAME

Beryl B. Knowles, North Attleboro, Mass., assignor to
Fairfield Optical Company, Mansfield, Mass., a corporation of Massachusetts

Filed Apr. 6, 1961, Ser. No. 64,640

Term of patent 7 years

(Cl. D57—1)

Fig. 1.

Fig. 2.

Fig. 3.

Fig. 4.

FIG. 1 is a perspective view of a spectacle frame embodying my new design;

FIG. 2 is a fragmentary front elevational view thereof taken on an enlarged scale;

FIG. 3 is a fragmentary top plan view thereof taken on an enlarged scale; and

FIG. 4 is a fragmentary side elevational view thereof taken on an enlarged scale.

The dominant features of my design reside in the portions shown in full lines.

I claim:

The ornamental design for a spectacle frame, substantially as shown and described.
